UNITED STATES PATENT OFFICE.

JACOB J. RETTMER, OF LUFKIN, TEXAS.

LUMBER-STAMPING DEVICE.

Application filed September 19, 1925. Serial No. 57,439.

My said invention relates to an improvement in a device for marking lumber. Heretofore it has been the custom to stamp or impress in the end of each piece of lumber the initials of the company or the like and this has been done by means of a die carrying the desired raised letters or indicia and the operation has been performed by striking with a hammer the end of the die after 10 said end had been inked thus forcing the die into the grain at the end of each piece of lumber and indenting the impression made. The workman performing this operation heretofore has usually carried a large apron 15 saturated with ink upon which he pressed the die after which he placed it against the end of the lumber and hammered the same to form an impression. Obviously the inking of the die was uncertain, the ink pad 20 was awkward to handle and became dry quickly as well as afforded a very prominent surface upon which the hands and clothes became soiled.

It is an object of the invention to provide a device of this character which will automatically supply ink to the operating surface between each stamping operation and which may be easily carried about and will be simple in construction and operation.

Referring to the accompanying drawings which are made a part hereof and on which similar reference characters indicate similar parts,

Figure 1 is a top plan view,

Figure 2, a side elevation,

Figure 3, a longitudinal vertical section,

Figure 4, an enlarged section on line 4-4 of Fig. 1, and

Figure 5 an enlarged detail view of the 40 sliding sleeve.

The invention comprises a body or frame having a cylindrical intermediate portion 10 and a pair of arms 11 formed integrally therewith and extending outwardly from said portion and spaced slightly from and parallel with said intermediate portion and disposed on opposite sides thereof. Each arm 11 is provided at its forward end with a small spike or projection 12 adapted to 45 bite into the article to be stamped and prevent relative movement between the stamp and the articles stamped during the stamping operation. The intermediate portion of the body is longitudinally bored for the reception of a die supporting and operating rod 13 upon the rear end of which is

fastened, by screw threads and a pin, a head or knob 14. The major part of the longitudinal bore of said intermediate portion is of a size slightly larger than the rod 13 to 60 permit free longitudinal movement of the rod but the forward portion of the bore is uniformly enlarged and a shoulder 15 is formed between the ends of the bores.

The rod 13 is provided with a collar 16 fixed thereto and adapted to seat on the shoulder 15 and prevent further rearward movement of the rod through the member 10. In order to maintain the rod in retracted position with the collar 16 against the shoulder 15 I provide a spring 17 about the rod between the confines of the end of the body 10 and the knob 14 and to provide better seats for the ends of the spring I form an annular channel in the end of each of 75 the confining members. The forward end of the rod 13 terminates short of the free ends of the arms 11 when the rod is in the retracted position and said rod is preferably formed with a reduced polygonal extremity 18 for the reception of a removable stamp or die member 19. By providing the reduced polygonal end the die member supported thereon will be prevented from rotation and a shoulder 20 is formed which 80 serves as a seat for the extremity of the die member. The reduced end 18 is provided on one of its flat faces with a leaf spring 21 for holding the die member on the same.

The die member 19 is provided with a 90 rearwardly extending shank in the end of which is formed a polygonal recess 22 for the reception of the end 18 of the rod 13, said recess having a depression at one side for the reception of the spring 21. A removable plate 23 having any desired indicia thereon is mounted on the forward end of said die member. The indicia is preferably of the raised type so that an impression may be made in the lumber which is marked. In its operative position the die or stamp is disposed longitudinally between the parallel arms 11 and to prevent the rod 13 supporting the same from rotating I provide a longitudinal slot 24 in the bore at the rear of the body and a pin 25 in the rod 13 for cooperation with said slot.

In order to supply the stamping member or die with ink I provide an ink pad 26 mounted in a frame 27 having an opening 28 for reception of ink forinking the pad. It is desirable to have this pad moved back and

forth over the end of the stamping member and I therefore mount the holder for the pad on a pair of arms 29, each supported on a bifurcated member 30 between the main body 10 and the arms 11. The bifurcated members are curved and the bifurcation in each is also curved, the said members being pivotally mounted upon a pin 32 extending through said body 10 and connecting the arms 11. The pin 32 is offset from the center of the body 10 and in order to reciprocate the pad over and away from the end of the die member I mount a sleeve 33 on the rod 13 and provide said sleeve with diametrically opposed arms 34 extending through slots 35 in the body 10, and terminating in the bifurcations of the members 30. These arms 34 have rollers 36 slipped over their ends and these rollers roll in the bifurcations and oscillate the ink pad.

In order to permit the device to be used in a close place as for example on the end of a board which is not flush with the others forming the collection, it is necessary to be able to perform the stamping operation with the ink pad in retracted position remote from the die member and to accomplish this function I provide means for releasing the sleeve 33 from the rod 13 including a spring 30 projected pin 37 mounted in a support 38 extending through a slot 39 in the sleeve 33 and having a top 40 by means of which said pin may be retracted and partially rotated so that the high portions of the support and cap engage and hold the pin out of engagement with a depression 41 in the rod 13. The end of the sleeve 33 adjacent the die member is provided with an enlarged bore 42 so that said sleeve may slip over the end of the die member and when in such position the ink pad will be in retracted position while the rod 13 may reciprocate freely therethrough.

From the foregoing it will be apparent that to stamp or impress indicia upon wood or material of similar character it will only be necessary to apply the projections 12 against the article to be impressed and strike the knob 14 with a hammer or other instrument to drive the raised letters into the material, they have first been linked by the ink pad 26. If it is desired to stamp an article which is in a recess the pin 37 may be retracted and the sleeve supporting the same pushed forward to retract the ink pad whereupon the device may be inserted and hammered as before.

It will be obvious to those skilled in the art that many changes may be made in my device without departing from the spirit of the invention and therefore I do not limit myself to what is shown in the drawings and described in the specification but only as indicated in the appended claims.

Having thus fully described my said in-

vention, what I claim as new and desire to secure by Letters Patent, is:

1. A device for stamping lumber comprising a body, an operating rod extending through said body and having a knob on one end and having its other end shaped for reception of a die member, means for preventing rotation between said body and said operating rod, guiding arms extending along said body on opposite sides thereof and forwardly of the die member for guiding the die member in its operation, anti-friction devices on the ends of said guiding arms, inking mechanism for said die member comprising a frame pivotally mounted on said body at one side of the center and adapted to swing to position over said die member and adapted to be retracted during the application of the die member to an object to be stamped said body having an enlarged bore at the end adjacent the die member, a sleeve in said bore between said body and said operating rod, means for causing said sleeve and operating rod to operate together or independently of each other, diametrically opposed arms on said sleeve extending through said body and having engagement with said inking mechanism whereby when the rod is reciprocated through said body the sleeve will be operated simultaneously and the inking mechanism will be swung into and out of position to ink said die member or will slide freely on said operating rod to permit the die member to be operated with the inking mechanism in retracted position, substantially as set forth.

2. A stamping device comprising a body, a rod extending through said body, a knob on the rear end of said rod, a die member on the forward end of said rod, arms on said body extending in parallel relation alongside said die member for guiding the same said rod having its end polygonally formed and reduced to provide a shoulder about the polygonal formation for engagement with a polygonal recess in the die member the extremity of said die member being adapted to seat upon the shoulder formed about the polygonal extremity of the operating rod, substantially as set forth.

3. A stamping device comprising a body, a rod longitudinally mounted in said body, a slot in said body, a pin on said rod extending into said slot for preventing relative rotation between the body and the rod, a knob on one end of said rod, a die member on the opposite end of said rod, arms on opposite sides of said body extending alongside of and parallel to said die member for guiding the same, means on the end of said arm for preventing slipping of the arm, a sleeve on said operating rod, a recess in said rod beneath said sleeve, a spring projected pin carried by said sleeve and adapted to engage the recess in the rod for preventing

relative movement between the sleeve and rod, arms extending outwardly on said sleeve, rollers on said arms, bifurcated members pivoted on said arms eccentrically to said sleeve for engagement with said rollers, supports extending from said bifurcated member, an inking pad carried at the end of said supports and positioned to engage over the end of said die member and ink the same, substantially as set forth.

4. A stamping device comprising a die member, a support for the die member, a housing for said support, means for inking said die member, and a connecting element between the support and the inking means operable by the support for actuating the inking means, said connecting element being capable of being temporarily rendered inoperable to permit the die member to be operated while the inking means remains idle, substantially as set forth.

5. A stamping device comprising a die member, a support for the die member, a housing for said support, means for inking said die member, and a sleeve carried by the support and operable therewith said sleeve having connection with the inking means for operating the same said sleeve being capable of being temporarily rendered inoperable to permit the die member to be operated while the inking means remains idle, substantially as set forth.

6. A stamping device comprising a die member, a support for the die member, a

housing for said support, means for preventing relative rotation between the housing and support, means pivoted on said housing for inking said die member, a sleeve fixed on the support and movable therewith having operative connection with the inking means for actuating the same, said sleeve being capable of being released from engagement with the support to permit the die member to be operated while the inking means remains idle, substantially as set forth.

7. A stamping device comprising a die member, a support for the die member, a housing for said support, means for preventing relative rotation between the housing and support, means pivoted on the housing to swing into engagement with the die member for inking the same, a sleeve on the support, a spring projected pin carried by the sleeve for engagement with the support whereby they are caused to move in unison, and arms on said sleeve having operative connection with the inking means for actuating the same said pin being adapted to be retracted to permit the support and die member to move through the sleeve while the inking means remains idle, substantially as set forth.

In witness whereof, I have hereunto set my hand and seal at Lufkin, Texas, this 16th day of September, A. D. nineteen hundred and twenty-five.

JACOB J. RETTMER. [L.S.]
